PRECAST CONCRETE METAL LINED PIPE

Filed June 13, 1927

UNITED STATES PATENT OFFICE

THOMAS DE LA MARE, OF SALT LAKE CITY, UTAH

PRECAST CONCRETE METAL-LINED PIPE

Application filed June 13, 1927. Serial No. 198,483.

This invention relates to a pre-cast concrete metal-lined pipe which shall:

First. Be strong and durable.

Second. Be susceptible to economical manufacture.

Third. Have a smooth inner surface.

Fourth. Have strong, fluid-tight joints when laid.

Fifth. Be simple to install.

Sixth. Be efficient in service.

Seventh. Provide convenient and efficient means for making bends in the pipe when laying.

In attaining these objects, I provide a continuous lining or hollow core, which is preferably made of light sheet metal, such as galvanized iron.

The pipe is preferably formed in pre-cast lengths of about 10 feet, and each length may

20 consist of a plurality, usually three, of sections of the metal lining, these sections being provided with slip joints so that the concrete in shrinking, shall not cause the lining to "buckle".

25 At the joints between the lengths, I provide flaring collars or bells, which may be formed separately from the linings and afterwards riveted, or otherwise secured, near the adjacent ends of consecutive lengths of the metal lining.

In pre-casting the pipe, one length of the lining is provided at each end with a suitable plug having a concentric spacing flange projecting outwardly therefrom. These plugs are held in place in any convenient manner, such as by a metal rod, threaded at both ends, passing through both plugs and provided with nuts to draw the plugs together against the ends of the lining. This length with the 40 plugs, is then placed in a suitable mold and concrete is cast around the lining to form a monolithic shell enclosing the lining.

Thus is defined at each end of a length of the pre-cast pipe, a metal-lined recess, this recess being exterior in relation to the lining and interior in relation to the collar and to the concrete shell.

In laying the pipe in the field, the adjacent ends of consecutive lengths are spaced apart 50 and joined by means of a sheet metal sleeve

which projects into one end of one length and over the lining of the adjacent end of the other length.

The circumferential edges of the opposing collars are perforated, and may be drawn or held together by means of tie-wires. The sleeve may be made substantially liquid-tight with respect to each length, by cementing or caulking in any suitable manner. Where it is desired to form a bend in the pipe, an elbow, instead of the sleeve, may be inserted between two consecutive lengths of the pipe.

After the joint has thus been caulked or cemented, concrete is poured around the joint, filling the flaring ends of the two lengths, as well as the space between them. The outside of the joint may be smoothed off to the diameter of the finished pipe, resulting in a smooth workmanlike job.

The features of this invention for which 70 the protection of Letters Patent is desired, are collectively grouped in the claims concluding this specification.

In the drawing,

Fig. 1 represents a longitudinal center section through a finished length of pre-cast pipe made in accordance with this invention;

Fig. 2, a similar section showing a set-up of the lining in the mold ready for the pouring of concrete;

Fig. 3, a detailed longitudinal center section through a joint between two lengths ready for the pouring of the concrete around the joints;

Fig. 4, same as Fig. 3, but showing joint completed;

Fig. 5, a cross-section on line 5, Fig. 2, after the concrete is poured;

Fig. 6, a longitudinal center section showing the method of forming a bend;

Fig. 7, a minor detail, in section; and

Fig. 8, a minor detail, in perspective.

Referring to the drawing, 10, 12, and 14 indicate sections of light sheet metal pipe, preferably galvanized iron, slip-jointed together as indicated at 15 and 16. One end of section 10 and one end of section 14 are provided with flaring collars 17, which may be riveted or otherwise fastened to the respective sections at 18. The collars 17 are ex- 100

ternally spaced apart from and substantially concentric with the lining, and thus provide the annular recesses 19.

In forming the concrete around the lining, 5 a plug 20 is inserted in each end thereof, each plug having the portion 20¹ extending into the lining, and the outwardly projecting spacing flange 20² transverse to the length of the lining. The plugs may be held in place 10 by means of the rod 27, the latter having both ends threaded and engaged by the nuts 28.

The mold in which the pipe is cast, may consist of the longitudinally extending base 15 portion 21, and the upper side portions 24 and 25, these being preferably hinged together as indicated at 26, Fig. 5.

In using the mold, the sections 10, 12 and 14 of the lining, together with the plugs 20 20 and the rod 27, are laid in the base portions of the mold, the upper side portions of the mold being opened out, as indicated by the dotted lines 24¹ and 25¹. This leaves the mold in shape to receive the concrete which can be 25 conveniently tamped into place, to approximately the level of the line 29 (Fig. 5). By now bringing the side portions 24¹ into the position indicated by the full lines 24, and tying the two portions 24 together substantially 30 along the line 30, more concrete may be poured and tamped, substantially to the level of the line 30. The portions 25 may now be brought into the final position indicated by the full lines, thus forming a longitudinal hopper by means of the integral flanges 31, into which the final amount of concrete may be poured, leaving that particular length of pipe in the finished pre-cast condition as shown in Fig. 1.

40 In laying the pipe in the field, the ends of two consecutive sections 32 and 34, are brought adjacent each other and spaced apart as shown in Fig. 3, the sleeve 35 having been previously slipped into place. In this instance, the right-hand end of sleeve 35 extends into the lining of length 34, and over the lining of length 32, so that liquid flowing through the pipe in the direction of the arrow, will run over the abutting edges 14¹ and 35¹, instead of running against these edges.

50 Wires 36 are threaded through the perforations 37 and twisted together as at 38, thereby tying the consecutive lengths of pre-cast pipe securely together. Any suitable material for 55 caulking may now be hammered into place, as at 39, and at 40, a strip of ordinary wire fly screen may be wrapped over the joint, and smeared over with white lead or other suitable plastic substance. Concrete may now 60 be poured into the open space between and within the collars of the lengths 32 and 34, bringing the pipe into the finished form shown in Fig. 4.

Where it is desired to form a bend between 65 two lengths such as 42 and 44, this may be

accomplished as indicated in Fig. 6, where instead of using a straight sleeve, a sheet metal elbow 45, may be inserted. The flaring collars of the two lengths are held together by means of the ties 46 and 47 in a manner similar to that already described.

70 Where this pipe is used for water mains, as in city streets, means must be provided for tapping the pipe for service connections. This I accomplish by casting inserts of metal, such as bronze, in the pipe when first made, as indicated in Figs. 5 and 7. The insert 48 may be provided with an annular rib 49, for securely anchoring the insert in the concrete shell. The inserts are tapped and provided with plugs 51. When it is desired to make a connection, the plug 51 is removed, and a service pipe such as 52, screwed into the insert. It frequently happens that it is desired to fasten the pipe 52 by other means in addition to the ordinary thread. To allow this to be done, a flange 50 may be threaded at 53, and cap screws 54 be used to fasten the reinforcing portion 60 to the flange 50.

75 This invention is particularly useful in 90 constructing the smaller sizes of pipes, such as from 1 inch to 12 inches inside diameter though it is not restricted thereto. To give an idea of the thickness of the material suitable for making the lining or hollow core, 95 for different diameters, the relations given following, are suggested. For 1 inch pipe, No. 30 galvanized iron; for 2 inch pipe, No. 28; for 4 inch pipe, No. 26; for 6 inch pipe, No. 24; and for 12 inch pipe, No. 16.

80 If desired, the concrete shell may be 100 strengthened by means of steel reinforcing 61 (Fig. 5) of any well known type.

While a specific embodiment of this invention is herein shown and described, it is to be 105 clearly understood that all the detailed parts thereof, may or may not be shown in the preferred forms, and further, that the preferred forms may be varied from time to time, as the development of this invention and the arts to which it appertains, progress. Therefore, that which forms an essential and characteristic part of this invention, will be 110 readily discernible from the claims in which its spirit is broadly generalized.

115 Having fully described my invention, what I claim is:

1. In a concrete pipe, a sheet metal lining, a shell of concrete pre-cast around said lining, and an annular recess defined at the end of said lining, said recess being longitudinally inward of an end face of said shell, exterior to said lining, and interior to said concrete shell; a second sheet metal lining similarly constructed and encased, said two linings spaced apart, a sleeve joining said linings, and a filling of concrete around said sleeve.

120 2. A length of pre-cast concrete pipe comprising sheet metal sections joined so as to 125

yield longitudinally in relation to one another, a shell of concrete around said lining, and a recess defined adjacent the end of said length of pipe, said recess being substantially 5 concentric with, and exterior to, said lining, and interior to said concrete shell; a second length of pre-cast pipe similarly constituted, said two lengths spaced apart, a sleeve joining said lengths within their recesses, and a 10 concrete filling around said sleeve.

3. A length of pre-cast concrete pipe comprising a metal lining, annular collars attached to said lining adjacent the ends thereof, and a concrete shell encasing said lining 15 and collars, thereby defining end recesses exterior to said lining and interior to said shell; a second length of pre-cast pipe similarly constituted, said two lengths spaced apart, a sleeve joining said lengths within their recesses, and a concrete filling around said sleeve. 20

4. A concrete pipe comprising a thin metal lining, flaring collars adjacent each end of said lining, perforations adjacent the free 25 edge of each collar, a shell of concrete encasing said lining and said collars; a second concrete pipe similarly constructed, said two pipes spaced apart end from end, a slip sleeve joining the adjacent ends, flexible ties extending 30 through said perforations in the adjacent collars, and a concrete filling around said slip sleeve and said ties.

5. A length of pre-cast concrete pipe comprising a sheet metal lining, a collar flaring 35 circumferentially adjacent an end of said lining and exterior thereto, a shell of concrete around said lining and said collar, a second length of pre-cast concrete pipe comprising a sheet metal lining having an end spaced apart 40 from the end of the first length, a collar flaring circumferentially adjacent the said spaced-apart end of the said second lining and exterior thereto, a shell of concrete around said second lining and collar, a sleeve connecting the adjacent ends of the two said linings, and a filling of concrete extending between 45 the opposite ends of the said concrete shells and into said flaring collars.

6. A length of pre-cast concrete pipe comprising a sheet metal lining, a collar flaring circumferentially adjacent an end of said lining and exterior thereto, a shell of concrete around said lining and said collar, a second 55 length of pre-cast concrete pipe comprising a sheet metal lining having an end spaced apart from the end of the first length, a collar flaring circumferentially adjacent the spaced-apart end of the said second lining and exterior thereto, a shell of concrete around said second lining and collar, a fitting connecting the adjacent ends of the two said linings, means tying the two said collars together, and a filling of concrete extending 60 around said tying means, between the oppo- 65

site ends of the said concrete shells and into said flaring collars.

7. A length of pre-cast concrete pipe comprising a sheet metal lining, a flaring collar at the end of said length and exterior thereto, 70 a shell of concrete around said lining, a second length of pre-cast concrete pipe having an end opposite and spaced apart from the collared end of the first length, a flaring collar adjacent the said opposite end of the second length, a fitting connecting the adjacent ends of the said lengths, and a filling of concrete between the opposite ends of the said lengths, said filling keying into said flaring collars. 75

8. A length of pre-cast concrete pipe comprising a sheet metal lining, a flaring collar at the end of said length and exterior thereto, a shell of concrete around said lining, a second length of pre-cast concrete pipe with a lining 80 having an end opposite the collared end of the first length, a flaring collar adjacent the said opposite end of the second length, a fitting slipped over the lining of one length and into the lining of the adjacent length, 85 packing material caulked between the collar of the said one length and the exterior surface of said fitting, a circumferential band of fabric extending partly over the end of the second lining and partly over the said fitting, 90 a plastic material in the interstices of said fabric, and a filling of concrete encasing the said fitting, said filling extending between 95 said lengths of pre-cast pipe.

In testimony whereof I sign my name 100 hereto.

THOMAS DE LA MARE.
